SAFETY DAMPER PREVENTING HEAT EMANATION FROM ABNORMAL POSITIONED HEATERS

George J. Moeller, Altadena, Calif., assignor to
Anthony Oberholtz, Los Angeles, Calif.

Application September 29, 1947, Serial No. 776,697

6 Claims. (Cl. 126—58)

1

This invention relates to means for improving the safety features of circulating electric heaters, such as disclosed in the pending application of Anthony Oberholtz and George J. Moeller, Serial No. 752,012, filed June 3, 1947, now matured into Patent No. 2,528,774 granted Nov. 7, 1950, said Oberholtz being the assignee of record of said application and of the instant application.

The primary object of the present invention is to provide, in such a heater, means that automatically closes the circulating means of the heater should the latter be inadvertently tipped over to thereby cut off the emanation of heat and obviate ignition of table cloths, doilies and other items upon which the tipped-over heater comes to rest.

Another object of the invention is to provide a heater with a weighted and universally mounted vane or damper that assumes the mentioned closure position upon tipping of the heater on its side.

Another object of the invention is to so form and mount the damper that the same will function effectively regardless of the direction in which the heater is tipped.

My invention also has for its objects to provide such means that are positive in operation, convenient in use, easily installed in a working position and easily disconnected therefrom, economical of manufacture, relatively simple, and of general superiority and serviceability.

The invention also comprises novel details of construction and novel combinations and arrangements of parts, which will more fully appear in the course of the following description. However, the drawings merely show and the following description merely describes one embodiment of the present invention, which is given by way of illustration or example only.

In the drawings, like reference characters designate similar parts in the several views.

Fig. 1 is a vertical sectional view of the upper portion of a heater provided with a safety damper according to the present invention.

Fig. 2 is a side view of the damper as seen from the left side of Fig. 1.

The heater that is illustrated comprises an outer housing tube 5, a preferably convexly formed grill 6 mounted over the top of said tube, an inner tube 7 within the housing tube and carried by the grill, and a heating element 8 located centrally in the lower portion of the inner tube 7. A support base is provided and the same is generally similar to that disclosed in the mentioned

pending application. Heat from the element 8 radiates upwardly in tube 7 and outwardly past grill 6, and air circulating in the annular space between the tubes serves to dissipate such heat that may be conducted through the wall of the inner tube to thereby keep the housing tube relatively cool.

Should the above heater be inadvertently tipped over, the same would come to rest on the edge of its base and on the upper edge of tube 5. Heat would then be directed in a substantially lateral direction and may ignite such inflammable material in the path of movement of the heat. The safety damper 9 of the present invention is provided to automatically close off the tube 7 and prevent such emanation of heat upon tipping over of the heater.

The safety damper 9 that is illustrated comprises, generally, a vane 10, a universal mount 11 for the vane, means 12 weighting the vane to assume a vertical position for all positions of the heater, and a support rod 13 for the vane from the grill 6.

The vane 10 is a preferably circular member fitting within tube 7 with sufficient clearance to move universally from a normal, nearly vertical position in the tube, to a transverse position therein. The vane is made of heat-resisting material and is relatively light in weight. It may be stiffened by embossments 14 and 15, the latter also serving to accommodate the mount 11 in close-coupled relationship. The middle of vane 10 is cut out as at 16 and is provided with a pair of opposed struck-up ears 17.

The mount 11 comprises an axially drilled tube 18 into which support rod 13 extends. A counterbore 19 is formed in the tube to provide a shoulder for a washer 20 on the end of support rod 13, and the latter is headed-over as at 21, to retain the washer in place. The tube 18 is freely rotatable on rod 13 and, in the vertical position of the heater, is suspended from the same. Somewhat spaced from the head 21, the tube 18 is provided with a transverse pin 22 that extends freely through ears 17. Thus, the vane is mounted to both swivel about rod 13 and pivot about pin 22.

The weight 12 is placed on the vane at a point remote from the mount 11 so that the weight over-balances the vane which, at all times, seeks a vertical position. Thus, with the heater vertical, the vane, as shown by the full-line position thereof, is vertical and forms no obstruction to the emanation of heat rising in tube 7. Should the heater become tipped toward the left, the vane

will simply over-balance and pivot on pin 22 to assume the dot-dash line position shown and thereby close off tube 7.

The weight 12, as best seen in Fig. 2, is placed to one side of the vertical center line of the vane so that the vane is over-balanced with respect to the axis of rod 13. Now, should the heater be tipped in any other direction—as to the right, for instance—the off-centered weight will first over-balance the vane to cause the same to swivel on rod 13, and then when said weight has swiveled the vane, the latter will then over-balance or pivot on pin 22 to close off tube 7, as before. It will be seen that the weight, gravitationally seeks a pendant or over-balanced position as the heater is tipped, so assurance is had that the same will swivel to a position from which it can pivot to the closure position. Upon restoration of the heater to an upright condition, the vane will automatically resume the full-line position of Fig. 1.

While I have illustrated and described what I now regard as the preferred embodiment of my invention, the construction is, of course, subject to modifications without departing from the spirit and scope of my invention. I, therefore, do not wish to restrict myself to the particular form of construction illustrated and described, but desire to avail myself of all modifications that may fall within the scope of the appended claims.

Having thus described my invention, what I claim and desire to secure by Letters Patent is:

1. In combination, a heater having a heat-emanating tube and a heat passing grill thereabove, a support member extending vertically from the grill into the tube, a horizontally movable swivel on the end of the support member, a transverse pivot on the swivel, a vane substantially centrally carried by the pivot, an off-center over-balancing weight on the vane below said pivot for positioning said vane vertically in the tube and for effecting swivelability of the vane upon tipping over of the heater, whereby said vane seeks to retain its vertical disposition during all tipped-over positions of the heater and thereby assumes a transverse position in the tube when the heater is tipped over.

2. A safety damper comprising a vane, a normally horizontal pivot for the vane and located substantially centrally thereof, a weight on the vane below the pivot for normally over-balancing said vane on its pivot to a vertical position, the weight being offset relative to the vertical middle of the vane, a normally vertical tube connected to said pivot, a support rod, said weight tending to over-balance the vane relative to the axis of the support rod, and a swivel connection between the support rod and the tube, whereby the vane and the support rod are relatively universally movable.

3. A safety damper comprising a vane, a normally horizontal pivot for the vane and located substantially centrally thereof, a weight on the vane below the pivot for normally over-balancing said vane on its pivot to a vertical position, a normally vertical tube connected to said pivot, a normally vertical support rod, and a swivel connection between the support rod and the tube, whereby the vane and the support rod are relatively universally movable, said weight being lo-

cated on the vane to one side of the vertical center thereof to gravitationally over-balance the vane to cause swiveling movement between the support rod and the vane and tube when the support rod is moved from its normally vertical position.

4. A safety damper for an electric heater comprising a normally vertically disposed heat-emanating tube, a vane disposed within said tube, a universal mount supported by the heater and connected substantially centrally to said vane, said mount comprising a swivel axial relative to the tube and a pivot transverse to the tube, a weight spaced from the mount and affixed to the vane to over-balance said vane on its pivot at all times disposing said vane in a substantially vertical position, said weight being off-center with respect to the vertical center of the vane to swivel the vane to a position enabling pivotal movement thereof when the heater is tipped over from its normal erect position.

5. The combination with a heater having a normally vertically disposed heat-emanating tube, of a safety damper disposed within said tube and adapted to automatically close said tube upon tipping over of the heater regardless of the direction the same is tipped, a universal mount supported by the heater and comprising both a normally vertical swivel and a normally horizontal pivot, the pivot being connected substantially centrally to the damper, and a weight on the damper below the horizontal pivot and offset relative to the normal vertical center of the damper, said weight at all times over-balancing the vane to a vertical position on its horizontal pivot and tending to over-balance the weight on its swivel upon tipping over of the heater and of the normally vertical swivel.

6. In combination, a heater having a normally vertical heat-emanating tube and a heat-passing grill thereabove, a support member extending vertically from the grill into the tube, a vertically disposed horizontally movable swivel on the end of the support member, a transverse horizontal pivot on the swivel, a vane substantially centrally carried by the pivot, an over-balancing weight on the vane below the pivot and offset with respect to the vertical center of the swivel to normally over-balance the vane to a vertical heat-passing position in said tube, said swivel and pivot constituting a universal mount for the vane that is automatically operative, upon tipping over of the heater to a substantially horizontal position of the tube thereof, to cause the offset weight to first swing the vane on the swivel and then over-balance the same on the pivot to retain the mentioned vertical disposition of the vane which, thereby, assumes a transverse heat-arresting position in said horizontally disposed tube.
